SHINGLE CONSTRUCTION

Floyd L. Worsham, Anniston, Ala.

Application August 27, 1946, Serial No. 693,225

3 Claims. (Cl. 108—7)

1

This invention relates to coverings primarily for roofs and the like including shingles and more particularly to improved composition shingles of sheet material such as asbestos impregnated with a suitable binder and provided with a suitable coating to eliminate tackiness of the binder and provide shingles of any desired color.

Composition shingles are widely used at present and are available in several forms. The shingles available at present fail to satisfy in some particulars.

For example, most shingles now available are so shaped that a considerable amount of waste is involved in cutting or otherwise detaching the shingles from strips or rolls of sheet material. Conventional shingles can be applied ordinarily in only one manner and can provide only one roof pattern, and where different patterns are desired several types of shingles have to be stocked. Present available shingles are also subject to curling after they have been in place on a roof for a comparatively short time, permitting water to be swept under the shingles by wind during a storm and in some cases making it possible for a moderately strong wind to loosen the shingles and remove them from the roof.

It is one of the objects of the present invention to provide an improved composition shingle so shaped that rows of shingles may be cut from suitable strips of sheet material with substantially no waste, the entire stamping or cutting operation can be performed rapidly and efficiently in a single operation, and shingles of the same shape may be laid in different ways to provide several different roof patterns.

It is a further object of the invention to provide improved composition shingles having means for locking extending portions of the shingles in place so that the shingles cannot curl after they have been applied to the roof and the roof will thus remain in satisfactory condition for an extended period of service.

It is also an object to provide an improved composition shingle having edge shoulders or notches functioning as guide means by which the shingles can be easily and quickly aligned with adjacent shingles to provide desired roof patterns.

Other objects and advantages will become apparent as the description proceeds in conjunction with the accompanying drawings wherein:

Fig. 1 is a plan view of a group of adjoining shingles showing the manner in which the shingles are stamped or cut from a strip of sheet

2

material without substantial waste of material; Fig. 2, a plan view of a single shingle;

Fig. 3, a plan view similar to Fig. 2 showing a somewhat modified form of shingle;

Fig. 4, a plan view of a group of shingles laid in a "Dutch lap" pattern;

Fig. 5, a plan view of a group of shingles laid to provide a hexagonal or "tile" pattern; and

Fig. 6, a plan view of a group of the same shingles laid to provide an "American lap" pattern.

With continued reference to the drawings and particularly to Fig. 1, each shingle, as generally designated at 10, comprises a substantially rectangular portion 11 having at one side thereof a tapered tongue or extension 12, the side edges of which converge at an angle of approximately 20° from the corresponding side of the rectangular portion to a straight end portion substantially parallel to the side of the rectangular portion 10 from which the tongue extends. At its outer end the tongue is provided with a substantially L-shaped slot or cut 13 extending from the end of the tongue to a hole 14 at the inner end of the slot.

At its wider or base end the tongue 12 is of less width than the rectangular portion 11 providing a shoulder 15 at one side thereof and a shoulder 16 at the opposite side, the shoulder 15 being wider than the shoulder 16.

The side of the rectangular portion extending from the shoulder 15 is provided with two inset shoulders 17 and 18 of a width not materially greater than one-fourth of the shoulder 15. The edge of the rectangular portion extending from the portion 16 has an outset shoulder 19 of approximately the same width as the shoulders 17 and 18 so that the edge of the rectangular portion opposite the edge from which the tongue extends has a length less than the edge from which the tongue extends by the width of the shoulder 18. The width of the shoulder 18 is such as to provide an appearance of conventional spacing between adjacent shingles when laid in the "American lap" pattern and the distance of this shoulder from the edge of the shingle opposite the tongue is substantially the same as the width of the exposed portions of overlapped wooden shingles.

The modified form of shingle shown in Fig. 3 is identical with the form shown in Fig. 2 except that the outer end of the tongue portion is provided with a C-shaped slot 20, the ends of which terminate in holes 21 and 22. The slots or cuts 13 and 20 provide means for locking down the 55 exposed tongue portions when the shingles are

laid in the hexagonal or tile pattern illustrated in Fig. 5.

When the shingles are laid in the "Dutch lap" pattern, illustrated in Fig. 4, the adjacent edge portions are overlapped. In the pattern illustrated in Fig. 4, the edge extending from the shoulder 16 of a shingle positioned to the right is lapped over the adjacent edge of a shingle positioned to the left until the outer corner of the shoulder 16 of the top shingle is coincident with the point of intersection of the right-hand edge of the tongue and the shoulder 15 of the bottom shingle. This leaves between the points of intersection of adjacent tongue edges of adjacent shingles a space equal in width to the shoulder 16. A course of shingles, overlapped as indicated, is applied to the roof and then a second course of overlapped shingles is applied over the first course with the lower edges of the second course overlapping the tongue portions of the first course and the adjacent rectangular portions up to the shoulders 17 and 19. As the shingles are applied to the roof, each shingle is fastened down by two nails, as indicated at 23 and 24, located at the two right-hand corners of the rectangular portions of the shingles, the nails being applied in such a manner that all nail heads are covered by overlapping shingle portions. The outer overlapping edges of the shingles are then secured to the roof by suitable corrosion resisting means, such as copper staples 25. In applying the shingles to form this "Dutch lap" pattern, the tongues are at the upper edges of the shingles, the edges of the shingles opposite the tongues being parallel to the edge of the roof at the eaves.

When the shingles are applied to form the hexagonal or tile pattern shown in Fig. 5, they are inverted in position so that the rectangular portions of the shingles are upward or toward the peak of the roof and the tongues are on the lower sides of the shingles extending toward the edge of the roof. In this case a first course of shingles is preferably laid in the upright position with the edges opposite the tongues parallel to and overhanging the edge of the roof at the edges. The succeeding courses of shingles, however, are inverted as illustrated in Fig. 5. In this case the edges of the shingles are not overlapped but are laid in abutting relationship while the courses are overlapped to an extent such that the shingles of an overlying course have their shoulders 17 and 19 along the edges opposite the tongues of the corresponding underlying course. This provides between adjacent shingles the spaces equal in width to the shoulders 18, but these spaces are covered by overlying courses and do not appear in the upper surface of the roof. As each superimposed course of shingles is laid, the cuts or slots 13 or 20 in the ends of the tongues are passed over the shoulder portions 15 of the corresponding shingles of the underlying course. This locks the lower ends of the tongues down firmly in position and prevents these extended portions of the shingles from curling.

The shingles are secured in position on the roof by means of fastening nails 26 inserted through the corners of the shingles adjacent the shoulders 15 and 16.

When the shingles are laid in the "American lap" pattern illustrated in Fig. 6, a first course is laid with the edges opposite the tongues or extensions parallel to and along the lower edge of the roof at the eaves. The adjacent edges of the shingles in the course are abutted in a man-

ner such that the shoulder 19 of one shingle overlies the shoulder 17 of an adjacent shingle, these shoulders providing a guide for laying the courses evenly as well as a lock against longitudinal movement of the shingles relative to each other. At the same time the shoulders 18 provide spaces between the lower portions of the rectangular parts of the shingles to give the appearance of conventional spacing of wooden shingles. The overlying course is positioned so that the edges of the shingles opposite the tongues lie along the shoulders 18 of the underlying course. This provides an extensive overlapping of the shingles such as to give a substantially three-ply roof and the exposed parts of the rectangular portions of the shingles have a width between their lower edges and the lower edges of the superimposed course so limited that any tendency of the shingles to curl is eliminated. In this pattern the shingles are secured to the roof by nails inserted through the rectangular portions of the shingles adjacent the edges having the shoulders 19 and 17 and at substantially half way of the width of the rectangular portions between the edges from which the tongues extend and the edges opposite the tongues. All nail heads in this case are covered by portions of superimposed shingles.

By reason of the particular shape of the improved shingles, as described above, the shingles may be cut from the sheet material without waste except for the small strips of sheet material between the shoulders 18 and the edges of the shingles opposite the extensions, as is clearly illustrated in Fig. 1. This amount of waste is entirely negligible. Also, the shingles can be laid in various patterns such as those illustrated in Figs. 4, 5 and 6 and are securely locked in place against curling or displacement by wind or weather.

It will be obvious to those skilled in the art that various changes may be made in the invention without departing from the spirit and scope thereof and therefore the invention is not limited by that which is shown in the drawing and described in the specification but only as indicated in the appended claims.

What is claimed is:

1. A composition shingle adapted to be laid in side by side relationship with similar shingles comprising a rectangular base portion and an integral truncated tongue portion extending from one edge thereof, an edge of the tongue portion and the edges of the base portion being substantially parallel to each other, one side of the base portion being provided with a parallel stepped-down portion forming a recess extending to the said one edge thereof, the opposite side of the base portion being provided with three progressively stepped down parallel edges of progressively increased lengths separated by shoulders, the uppermost of said edges being of identical length and depth with the recess provided in the opposite side of the base portion whereby when a plurality of shingles are laid in side by side relationship to form a pattern the uppermost of said stepped-down edges will be received within the recess in the side of the adjacent shingle, the intermediate stepped-down portion will abut the side of the adjacent shingle adjoining the recess therein, and the lowermost of said stepped-down portions will provide a space between adjacent shingles, said truncated tongue portion being provided with an angular slot in the outer end thereof providing a locking

tab to be inserted beneath the edge portion of an adjacent shingle.

2. A shingle as set forth in claim 1 wherein said slot is L-shaped extending inwardly from the outer edge of the tongue, one leg of the slot being substantially parallel to said outer edge.

3. A shingle as set forth in claim 1 wherein said slot is C-shaped, the top and bottom legs of said slot being substantially parallel to the outer edge of said truncated tongue.
